CLOSURE FASTENER

William J. Goodman and John W. Lang,
Milltown, N. J.

Application November 22, 1933, Serial No. 699,256

4 Claims. (Cl. 292—11)

This invention relates to the class of closure fasteners and has as its object the provision of a device of this character especially adapted for use with windows for securing the latter locked.

5 More specifically the invention comprises a locking mechanism comprising a bolt movable outwardly from a casing into engagement with a keeper, together with an arcuate locking bolt also movable outwardly from the casing and into engagement with suitable means provided on the keeper in a manner to draw the parts of the closure closer together, as well as to serve as a means for effectively preventing "jimmying" of the lock.

10

15 The invention together with its objects and advantages will be best understood from a study of the following description taken in connection with the accompanying drawing wherein:

Figure 1 is a view illustrating the application
20 of the invention to a window.

Figure 2 is a sectional view through the lock
with one bolt in operative engagement with the

Figure 3 is a view similar to Figure 2 and showing the arcuate bolt in operative position for drawing the lock parts closer together.

Figure 4 is a bottom plan view of the device and Figure 5 is an end elevational view of the bolt.

30 Referring to the drawing by reference numerals it will be seen that the lock comprises a suit-

35 as it will be seen that the lock comprises a suitable casing 10 having attaching flanges 11 whereby it may be readily secured to the top rail 12 of the lower sliding sash indicated generally by the reference numeral 13. Rockably mounted transversely of the casing 10 adjacent the open side thereof is a shaft 14 on which is loosely pivoted a locking bolt 15 that is normally urged outwardly of the casing 10, or to a projected position 40 through the medium of a suitable coil spring 16, one end of which as clearly shown in Figure 2 bears behind the bolt 15 and the other end of which bears against a suitable ledge 17 provided at the rear or closed end of the casing 10. The 45 bolt 15 as shown is of somewhat segmental shape in cross section and is adapted to project into a keeper 18, which latter, as shown is of casing like construction and is provided with a suitable flange 19 whereby it may be secured through the 50 medium of suitable fastening elements to the lower rail 12a of the upper sliding sash 13a.

As clearly shown in Figure 2 the bolt 15 is provided with a suitable slot 20 effectively located to prevent a separation of the bolt and keeper by means of a jimmy or other tool when inserted be-

tween the window frame as is often effective in obtaining an opening of a window equipped with locks of the type now generally employed.

A second or auxiliary bolt 21 is provided and has an arcuate portion as shown. The bolt 21 is secured through the medium of a pin 22 to the shaft 14 and when projected into the keeper 18 upon rotation of the shaft 14 in a clockwise direction is adapted to engage a keeper pin 23 provided interiorly of the keeper 18 in a manner shown in Figure 3 for drawing the window frames closer together and more effectively lock the window.

Provided on one end of the bolt 15 is a pin 24 that operates in a notch 25 provided adjacent the pivoted end of a bolt 21. It will thus be seen that when the handle or finger piece 26 provided on one end of the shaft 14 is swung to the dotted line position shown in Figure 1 the bolt 21 will be projected beyond the bolt 15 in a manner to engage the pin 23, and the cam action of the bolt 21 on the pin 23 during the extended projection thereof as just described will serve to draw the parts of the closure, in the present instance the window sashes closer together. Also, when the handle or finger piece 26 is swung in an anti-clockwise direction causing the bolt 21 to swing therewith the notch portion 25 of the bolt will engage the pin 24 for transmitting movement of the bolt 21 to the bolt 15 to cause the latter to also swing in an anti-clockwise direction out of engagement with the keeper 18 for unlocking the window.

Having thus described the invention, what is claimed as new is:

1. A closure fastener comprising a locking bolt movable in a curved path, a rockably mounted shaft about which the bolt moves as a pivot, spring means engaged with the bolt for normally urging it to projected position, a second locking bolt fixed to the shaft and movable therewith in a curved path, the second bolt having a notched portion adjacent its pivoted end, and the first named bolt having a pin extending therefrom and operating in the notch portion of the second named bolt for transmitting movement of the shaft to the first named bolt for simultaneously retracting both of said bolts, and a handle connected with the shaft. 44

2. A lock comprising a casing, a shaft rockably mounted in said casing, a handle connected with the shaft, a bolt rotatably mounted on said shaft and movable in a path concentric to the shaft as an axis, a curved locking bolt secured to the shaft and movable therewith, spring 5

means for normally holding the first bolt in projected position, and interengaging means on the spring bolt and said second bolt for transmitting movement of the second bolt to the first bolt to retract the first bolt when the second bolt is retracted.

3. In a lock of the class described, a casing, a shaft supported for rocking movement in the casing and having one end projecting therefrom, a handle connected with said projecting end, a curved locking bolt secured to the shaft, a second bolt of substantially segmental shape rotatably mounted on said shaft, a spring for normally holding the second bolt in projected position and a pin carried by the second bolt for moving the curved bolt into partly projected position when the spring has projected the second bolt and said pin retracting the second bolt when the curved bolt has been manually moved to retracted position.

4. In a lock of the class described, a casing, a shaft supported for rocking movement in the casing and having one end projecting therefrom, a handle rising from said projecting end, a curved locking bolt secured to the shaft, a second bolt of substantially segmental form rotatably mounted on said shaft, a spring for normally holding the second bolt in projected position, a pin carried by the second bolt for moving the curved bolt into partly projected position when the spring has projected the second bolt and said pin retracting the second bolt when the curved bolt has been manually moved to retracted position, and said second bolt having a slot in the under portion of its forward part, said slot aligning with the space between the casing and a keeper member when the second bolt is in projected position.
